DIE OR ANCHOR FOR TACK BUTTONS

Franklin R. White, Waterbury, Conn., assignor
to The Patent Button Company, Waterbury,
Conn., a corporation of Connecticut

Application June 18, 1932, Serial No. 618,071

2 Claims. (Cl. 79—3)

My invention relates to new and useful improvements in dies or anchors for tack buttons, and has for an object to produce a die or anchor from a thin metal ribbon and to so cut the blanks from the ribbon that there will be absolutely no waste.

Still another object of the invention is to produce these dies or anchors from a thin metal strip, which is cut into the necessary length 10 blanks and the blanks, in turn, drawn to form a shell, after which the shell is to be finished in either one or two forms, as will be shortly explained.

Still another object of the invention is to 15 produce a small die made from blanks cut from a relatively thin ribbon, the opposite ends of the blank being supplements of each other, so that there is no metal wasted in the cutting of these blanks.

Still another object of the invention is to 20 provide a method of making these small anchors or dies, so that they may be made quickly in large quantities at relatively little cost after the proper dies have once been provided.

With these and other objects in view, the 25 invention consists in certain new and novel arrangements and combination of parts, as will be hereinafter more fully described and pointed out in the claims.

Referring now to the drawing showing several 30 forms of blanks and showing two ways in which the finished dies or anchors may be made up,

Fig. 1 is a view of a piece of ribbon stock showing the manner in which the blanks are to 35 be cut;

Fig. 2 is a view showing a blank drawn into a shell, the shell pressed into its final form, and a bottom view of the die;

Fig. 3 is a view similar to Fig. 1;

Fig. 4 shows a shell, and a slightly different 40 manner in which the finished die may be made up;

Fig. 5 shows a piece of ribbon stock cut into blanks of a slightly different form;

Fig. 6 shows the shell and the resultant die; 45 Fig. 7 is a view similar to Fig. 5;

Fig. 8 shows a shell and a die somewhat similar to the die shown in Fig. 4;

Fig. 9 illustrates still a third way in which 50 the blanks may be cut from the ribbon stock;

Fig. 10 shows the drawn shell and a slightly different form of die, that is, with a dome head;

Fig. 11 is a view similar to Fig. 9; and

Fig. 12 shows a drawn shell, and a completed 55 die very similar to the die shown in Fig. 8.

Referring now to the drawing, and for the moment to Fig. 1, there is shown a fragmentary portion of a ribbon 1 preferably made of thin steel, and it will be noticed that the forward end 60 is cut in angular formation, as at 2, while a

similar cut is made, as at 3, to complete the first blank A and to also form the forward end of the second blank B. Likewise, the next cut 4 will form the rear of the blank B and the beginning of the blank C, ad infinitum.

From this, it will be seen that the metal of the ribbon blank is entirely utilized in making the little dies or anchors, the only metal, of course, being wasted being the metal displaced by the kerf or cut. I have not shown the dies 10 for cutting the blank ribbon or for drawing the blank or form but this practice is well understood and needs no further consideration.

Now taking one of the blanks A, for example, it is placed in the proper die and drawn into a 15 shell D, the greater part of the draw being from the point 5 to its top 6, while the corners or ends 7 of the blank are also being pressed inwardly to thus complete the little shell, as shown in the first view of Fig. 2. The little shell 20 D is then placed in the proper die (not shown) and the dome 8 is flattened down to form the top or head 9 of the little completed die or anchor, while the ends or former corners 7 of the blank are curled inwardly and upwardly, so 25 that they assume the position as shown at 10.

It will be noticed that the shell D just below the top is pressed in or restricted, as at 11, to 30 form the under surface of the head and also the hub 12. It will be seen that by constricting the shell, as shown, there is also formed a small chamber 13 in the head of the die which is to receive the prong of a tack (not shown), which tack, in turn, when the button is attached in the usual button attaching machines, will be 35 deformed and clenched over the ends or the corners, that now form the bottom of the little die or anchor.

I have not shown the tack in position, as 40 similar type dies and anchors that are to be placed in buttons are well known to those skilled in the art. It is also understood, of course, that these little dies or anchors are placed in the hollow hubs of shell buttons and a tack driven up through the bottom of the hub, up through 45 the die, and there deformed within the die to hold the button in place.

It will be seen that by forming a die of metal stock cut as shown, there is no waste whatever of the metal ribbon and with the proper dies it 50 is a simple matter to cut the blank into the form first shown in Fig. 1 and then draw the form to a shell and, lastly, compress the shell and force the side walls inwardly and the bottom points upwardly, thus completing the die.

The third illustration in Fig. 2 is a bottom plan view of the completed die showing how the metal is compressed and showing the opening through which the tack passes up into the die.

Referring now to Figs. 3 and 4, the same form 60

of ribbon stock F is shown cut into blanks and a shell 14 is shown, which is formed or drawn similar to the one shown in Fig. 2.

After the shell is so formed, however, it is then further acted upon to produce the little die or anchor 15. This die has the flat top 16, the tapered wall 17, and the restricted hub 18.

In this instance, the hub portion 18 is narrower than the hub of the die shown in Fig. 2 and the hollow hub will have a diameter just slightly larger than the prong of the tack fastener.

In constricting the shell, the points 19 (corners) will be pressed together, as shown at 20, to thus practically close up the space between the points 19 of the shell, as shown in the first view of Fig. 4. Also, in constricting the hub, it will be seen that the metal of the points (corners) is not only forced together but slightly twisted.

When a tack is driven up through the hub of a button (not shown) and into this die or anchor, it will also be deformed against the upper inner wall of the die, and in deforming will assume a greater diameter than the diameter of the hollow hub to thus tightly anchor the die and button in place.

Now in Figs. 5 and 7, I have shown how the ribbon stock may be cut in a different way from that shown in Figs. 1 and 3 and, at the same time, produce the desired blanks without any loss of metal.

Referring for the moment to Fig. 5, there is shown the metal strip 1' and the blanks A', B', and C', and it will be seen that, taking one of the blanks for example, say A', there is a cut-away portion at one end, as at 21, leaving the resultant tongue 22 above the same. The rear of the blank A' will have a cut-away portion 23 and a resultant tongue 24. However, the tongue 24 is diagonally positioned with regard to the tongue 22. Thus, it will be seen that by cutting the ribbon blank in this manner, the one end is a supplement of the other, in this way utilizing all of the ribbon stock to make up the multiple blanks.

The blank is then drawn into the shell 25, and it will be noticed that two corners 26 are slightly shorter than the others but when the die is pressed into its final shape and constricted, as at 27, the lower edges of the points of the shells will be turned upwardly and inwardly, as at 28, where any difference in length of these resultant points would not be of any disadvantage.

In Figs. 7 and 8, the same manner is used in cutting the blanks A'', and the shell 25' is similar to the shell 25, whereas the little resultant die 26', after pressed into shape, will be very similar to the die 15, the only difference being the metal along the lower edge of the hub of the die.

Referring now to Figs. 9 to 12 inclusive, there is still a third way of cutting this ribbon stock 1^b into little blanks A³. In this instance, the blank is cut with a tongue 30 centrally of the blank at one end and two small tongues 31 at the rear of the blank. Thus, in cutting the rear of the blank A³, the front of the succeeding blank will be formed, as is perfectly obvious.

In Fig. 10, I have shown the little shell 33 drawn from the blank with its dome 34 and,

if desired, I can form the resultant die 35 slightly different from the dies 11 and 27, that is, I can compress the walls, as at 36, compress the hub, as at 37, but leave a small circular dome 38, as may be clearly seen. This small dome might be formed in the other dies above-described.

The lower ends 39 (corners) of the shell will be pressed inwardly and slightly upwardly (not shown) similar to the ends of the die shown in Figs. 2 and 6.

In Figs. 11 and 12, the little blanks are cut in the same manner, and a shell 33' may be pressed to have a flat head 40, if desired, while the little hub 41 will have a short end, as at 42, but when the little shell is constricted to form the narrow hub, the space between the corners will be fairly well filled up, and inasmuch as the tack is to be forced up into the head of the die or hollow chamber of the die, the short end is no detriment.

From the foregoing, it will be seen that in all three forms I utilize a metal ribbon and cut the ends so that the one is supplementary to the other. In this way, there will be no metal wasted in the manufacture of these little anchors or dies.

Also, the metal is then drawn into a slightly elongated shell, after which the side of the shell is pressed inwardly to form an upper chamber in the die while the lower ends of the shell may be either turned inwardly and slightly upwardly, as shown in the one form, or may be just swedged or squeezed together to produce the other form of die.

It will also be noticed that after the shell is drawn to shape, there is considerably less stock to be turned up in the shell or to form the shank of the other form of die. This has two advantages. First, it provides stock wide enough to form a substantial solid walled head and, second, calls for much less pressure and strain on the tools when completing the die or anchor.

Many slight changes are possible without in any way departing from the spirit of the invention.

Having thus described my invention, what I claim as new and desire to secure by Letters Patent is:—

1. The method of forming a die for tack buttons which consists in cutting blanks of steel ribbon stock, the forward end of the blank being the reverse of the rear end, drawing the blank into a shell having a rounded bottom and serrated rim, and the serrations being of varying lengths due to the shape of the cut blank, compressing the dome of the shell to form a head, drawing in the remainder of the shell to form a restricted hub, and forcing the uneven length serrations up into the hub to provide a guide for a tack.

2. The method of forming a die for tack buttons which consists in cutting blanks of steel ribbon stock, the forward end of the blank being the reverse of the rear, drawing the blank into a shell, compressing the dome of the shell, and constricting the side walls of the shell to form a hollow head and a constricted hollow hub, the lower edge of the hub having serrations or teeth of different lengths, said teeth being turned upwardly within the hub at their base to form a guideway within the hub for a tack.
